UNITED STATES PATENT OFFICE.

WILLIAM TRAIT GRAY, OF TIMPERLEY, CHESTER, ENGLAND, ASSIGNOR TO WESTINGHOUSE ELECTRIC & MANUFACTURING COMPANY, A CORPORATION OF PENNSYLVANIA.

COUPLER FOR TRAIN LINES.

Application filed January 11, 1923, Serial No. 611,897, and in Great Britain January 11, 1922.

My invention relates to couplers or jumpers for the train lines or conductors between the units of electrical trains and it has special relation to couplers for train lines or conductors carrying current at high voltage.

An object of my invention is to provide a coupler of the type described above having such construction that the disconnection of the jumper from its receptacle effects disconnection of the train line from its source of current.

Another object of my invention is to provide means in the receptacle of the jumper whereby the energization of the train line cannot be effected until the jumper connection has been made and de-energization of the train line will be effected before the jumper can be disconnected.

Another object of my invention is to provide means actuated by the disconnection of any jumper for de-energizing the entire train line in a system of control for train-lines wherein the train line is composed of separate sections connected together by a jumper device and each section is separately energized from a common supply conductor.

Further objects, as well as details of construction whereby my invention may be utilized, will become evident from the accompanying drawings, in which

Figure 1 is a sectional side elevation of a coupler receptacle and jumper head,

Fig. 2 is a front view of the receptacle, partly broken away,

Fig. 3 is a diagrammatic representation of a train-line system in which my invention may be employed,

Fig. 4 is a side elevation, partly in section, of a modification of my invention,

Fig. 5 is a plan view of a portion of the device shown in Fig. 4, and

Fig. 6 is a diagrammatic representation of the train-line system in which the system shown in Fig. 4 may be employed.

Referring first to Figs. 1 and 2 of the drawings, the structure here shown comprises a receptacle 1 of a coupling that is mounted upon the end of a coach or unit of an electric train and that contains a coupling member 2, such as a split plug or the like, which is disposed in a mounting 3 of insulating material. The receptacle 1 is adapted to receive

the head 4 of an insulated coupler or jumper conductor 5. The jumper head 4 carries a connecting socket 57 which is disposed in a mounting 6 of insulating material and is adapted to receive the plug 2. The parts so far described may be of any desired construction and, since they form no part of the present invention, a detailed description thereof is considered unnecessary.

The receptacle 1 is provided with a box-like casing 7, which is preferably integral therewith and located at the upper front end of the receptacle and provided with a removable lid 8, which may be secured to the casing 7 by screws 9, or in any other convenient manner.

The jumper head 4 is provided with a lateral projection 10 (see Fig. 2), and the front extension of the receptacle 1 is provided with an internal longitudinal groove 11, which will permit the jumper head 4 to be inserted in the receptacle 1 when the projection 10 is registered with the groove 11. A slot 12 is formed through the lower wall of the box-like casing 7, the said slot crossing the groove 11 at the inner end of the latter and constituting, in conjunction with the slot, a joint or fastening of the bayonet-socket type.

Within the box-like casing 7 is mounted a control switch device that is adapted to be operated by the projection 10 when the jumper head 4 is placed within the receptacle and given a final rotary movement. The control switch shown comprises a pair of parallel stationary contact members 13 and 14, which are transversely disposed with respect to the receptacle and supported upon a back plate 15 of insulating material, which is, in turn, secured by screws 16 upon the rear wall of the box-like casing 7. Control circuit wires or conductors connected to the contact members 13 and 14 may be brought through the opening 58 that is provided in the back of the casing 7.

The parallel contact members 13 and 14 are adapted to be bridged by means of a movable contact member 17 in the form of a cross bar and mounted upon a block 18 of insulating material that is carried upon a rod 19, which is secured between the side walls of the casing 7. The block 18 is adapted to slide on the rod 19 in a transverse direction. The

parallel contact members 13 and 14 are provided with corresponding depressions 20, so that, when the bridging member 17 occupies the central position shown in Fig. 2, the contact members 13 and 14 will be bridged, and when, the bar 17 is moved to the left (referring to Fig. 2), it will be obvious that the contact members 13 and 14 will be disconnected. A spring is interposed between the block 18 and the right-hand wall of the casing 7 to maintain the bar 17 normally in the left-hand position, wherein the contact members 13 and 14 are disconnected. The block 18 is provided, on its under side, with a pair of lugs 22 and 23, which pass into the slot 12 and lie in the path of the projection 10 upon the jumper head 4. The arrangement is such that, when the said head is rotatively actuated, the block 18 will be reciprocated along the rod 19, and the contact members 13 and 14 will be either bridge or disconnected, according to the movements imparted to the jumper head. Thus, when the jumper head is actuated in a clockwise direction (Fig. 2), the contact members 13 and 14 will be bridged, so that the control switch will be closed, and this result will be effected against the action of the spring 21.

With this arrangement, in withdrawing the jumper head 4, the latter must be first actuated in a counter-clockwise direction, thus opening the control switch and releasing the jumper-head fastening, the spring 21 assisting the movement. In the event of the spring 21 becoming inoperative for any reason, the projection 10 on the jumper head will engage the left-hand projection 22 on the block 18 and will positively open the switch.

In order to prevent the spring 21 from rotating the jumper head 4 when the latter has been properly inserted in the receptacle 1, and the control switch closed, a projection 24 may be provided on the exterior of the jumper head 4, and a co-operating projection 25 provided upon the usual hinged lid or cover 26 of the receptacle 1. When the jumper is removed, the cover or lid 26 normally closes the mouth of the receptacle 1, and when the jumper head 4 is inserted into the receptacle, the lid or cover 26 must necessarily be open. After the head 4 has been rotated to close the control switch and fasten the coupling, the said lid or cover 26 may be dropped so that the projection 25 engages the left hand side of the projection 24 and thereby prevents counterclockwise rotation of the jumper head. The latter may be readily released by raising the lid or cover 26.

Referring now to Fig. 3, the jumpers of a three-coach or three-unit train are indicated diagrammatically at 5 and the control switches are indicated at 17. The contact members 13 and 14 of all the receptacles are connected in a series circuit 27 through additional couplers or jumpers conductors 28, the

said circuit containing the actuating coils 29 of contactor switches 30, of which there is one in each coach or unit of the train.

At the ends of the train, the circuit 27 is adapted to be connected, by means of two-way switches 31, respectively to a supply conductor 32 that is connected to a source of low-potential current and to a ground connection 33.

The contactor switches 30 serve to connect a train line 34 with high-potential supply conductors 35 in each coach or unit, when the coils 29 are energized.

With the above described arrangement, it will be obvious that immediately any attempt is made to remove a jumper head from a receptacle, the corresponding control switch 17 will be opened by reason of the necessary initial rotary movement that is required for the removal of the jumper head and, since all the control switches 17 are connected in series circuit 27, the train line 34 will be immediately disconnected from the high-potential supply conductors 35 by the opening of all the contactor switches 30. It will also be observed that, with the described circuits, the train line 34 will remain de-energized unless all the jumpers of the train line are properly connected. It is obvious also that a time element will be provided whereby a train line must be completely de-energized before the contact members 2 and 5 of the receptacle and jumper become in any way accessible, by reason of the necessity of rotating the jumper head before withdrawing it from the receptacle.

Instead of an electrically-controlled interlocking arrangement, as above described, contactor switches 30 may be controlled pneumatically, and an arrangement of the jumper receptacle for compressed air control, which is illustrated in Fig. 4, will now be described with reference to this figure and also to Figs. 5 and 6.

The contact switches 30 (Fig. 6) are of the pneumatically operated type, being connected to pistons 36 that operate in cylinders 37. The cylinders 37 are connected to a specially provided train pipe 38 which is connected between coaches or units of the train by air jumpers 39. The jumpers 39 are interlocked with the jumpers 5 of the train line 34 which is adapted to be connected to the high-tension supply conductor 35 in each coach or unit by means of the contactor switches 30. The contactor switches 30 are normally maintained in the open position by means of springs 40 that are disposed within the cylinders 37. The jumper receptacles of the train line 34 are provided with depending portions 41 (Fig. 4) to which the ends of the sections of the train-pipes 38 may be connected by a union 42, or in any other convenient manner.

Each depending portion 41 is provided

with a bore 43 in direct communication with the train pipe 38, the bore 43 further communicating by a duct 43^a with a vertical opening 44, which is adapted to be placed in communication with the air jumper 39. The air jumper 39 is connected to a head or terminal member 45 (Figs. 4 and 5), which is provided with a horizontal bore 46 that communicates with an arcuate opening 47. The terminal member 45 is adapted to be connected to the depending portion 41 by means of a locking bolt 48 having a screw-threaded end 49 engaging the depending portion 41 of the receptacle and also having a handle 50. The terminal member 45 is provided with a slot 51 to enable it to be placed in position or removed without the necessity of the complete removal of the terminal bolt 48.

When the terminal member 45 is in position beneath the portion 41, the opening 47 registers with the opening 44 so that a gas-tight connection is established between the train pipe 38 and the jumper 39. The interlock between the electrical jumper head 4 and the jumper receptacle 1 on the one hand and the pneumatic system on the other hand is provided by means of the bolt 48, the extreme end 52 of which projects within the bore of the receptacle 1 and is adapted to engage a hole or slot 53. With this arrangement, it is necessary to insert the jumper head before the pneumatic jumper 39 can be connected.

It will be seen from the foregoing description that, when all the pneumatic jumpers are properly connected, the compressed air supplied to the train line 38 will operate each of the pistons 36 to close the contactor switches 30, thereby connecting the train line 34 to the high-tension supply conductor 35. On the other hand, as soon as any attempt is made to release the jumper 4 from receptacle 1 by unscrewing the bolt 48, a leak in the air system will be immediately established, and the pressure behind the pistons 36 will be released, so that all the contactor switches will open and disconnect the train line 34 from the high-tension supply conductor.

A time element is provided by reason of the fact that the end 52 of the bolt 48 is designed to project into the hole or slot 53 in the jumper head 4 to a distance corresponding to several threads of the portion 39, the said threads being preferably of a relatively fine pitch so that the bolt must be turned several times before the jumper head is released.

In places where a receptacle 1 is not required to receive a jumper, for example, at the ends of the train, the train pipe 38 may be closed by means of a seal constituted by a dummy terminal member 54, which may be secured to the lid or cover 57, as illustrated in Fig. 4. The dummy terminal member 54

is similar in shape to the terminal member 45 of the pneumatic jumper 39, except that it has no air passage and simply constitutes an air-tight cover for the opening 44 and may be fastened by means of the bolt 48 in a manner already described in connection with the terminal member 45.

Furthermore, the previously described interlocking arrangement may be provided by means of a projection 55 also carried on the lid or cover 26 and designed, when said lid is in the closed position, to project into the lower part of the receptacle 1, the said projection 55 having a hole 56, the function of which is exactly the same as the hole 53 in the jumper head 4.

I do not wish to be restricted to the specific circuits or arrangement of parts herein set forth, as it is evident that various modifications thereof may be made within the spirit and scope of the invention. I desire, therefore, that only such limitations shall be imposed as are set forth in the appended claims.

I claim as my invention:

1. In a system comprising sections of a train-line conductor, in combination, complementary switch members for connecting the train-line conductor sections to establish a circuit, and means adapted to be actuated by the switch members to control the circuit through said conductor sections, said control means being disposed to effect the closure of the circuit after the switch members are set in engagement and the opening of the circuit before the switch members are separated.

2. In a system comprising sections of a train-line conductor, in combination, complementary switch members for connecting the train-line conductor sections to establish a circuit, means for locking the switch members in engagement, and means actuated as said locking means is operated to effect the control of the circuit through the conductor sections, said control means being disposed to effect the closure of the circuits after the switch members are in engagement and the opening of the circuit before the switch members are separated.

3. In a train-line jumper system, in combination, a plurality of train-line conductor sections, complementary switch members for connecting the conductor sections to establish a train-line circuit, electro-magnetic switches connected in the conductor sections, an actuating circuit for the electromagnetic switches and an auxiliary switch for controlling the switch-actuating circuit disposed to be operated by one of the complementary switch members.

4. In a train-line jumper system, in combination, a plurality of train-line conductor sections, complementary switch members for connecting the conductor sections to establish

- a train-line circuit, electromagnetic switches connected in the conductor sections, an actuating circuit for the electromagnetic switches, an auxiliary switch for controlling the switch-actuating circuit, means for locking the complementary switch members in engagement, said auxiliary switch and said locking means being disposed for operation by the relative movement of the complementary switch members when they are in engagement with one another.
5. In a train-line jumper system, in combination, a plurality of train-line conductor sections, complementary switch members for connecting the conductor sections to establish a train-line circuit, electromagnetic switches connected in the conductor sections, an actuating circuit for the electromagnetic switches and an auxiliary switch for controlling the switch-actuating circuit, said auxiliary switch being disposed for operation by one of the complementary switch members when rotated relative to the other switch
- 10
- 15
- 20

member to establish a positive engagement between said switch members.

6. In a train-line jumper system, in combination, a plurality of train-line conductor sections, complementary switch members for connecting the conductor sections to establish a train-line circuit, electromagnetic switches connected in the conductor sections, an actuating circuit for the electromagnetic switches, an auxiliary switch for controlling said switch-actuating circuit, said auxiliary switch being disposed for operation to its closed position after the train-line conductor sections have been connected and its open position before the train-line conductor sections are disconnected, thereby to provide a time element between the functioning of the complementary switch sections and the actuation of the electromagnetic switches.

In testimony whereof, I have hereunto subscribed my name this 28th day of December 1922.

WM. TRAIT GRAY.
